(57) **CLAIM**

The ornamental design for a portion of a front face of a vehicle wheel, as shown and described.

DESCRIPTION

FIG. 1 is a portion of a front view of a wheel showing my new design;

FIG. 2 is a portion of a bottom and front side perspective view of the wheel shown in FIG. 1; and,

FIG. 3 is a portion of a different left and front side perspective view of the wheel shown in FIG. 1.

Throughout the various figures of the drawings, certain views are not provided. The omission of a particular view is intended to convey that the element(s) depicted is/are plain and unornamented in that omitted view, or that the particular ornamental appearance in that view is simply not claimed. Where included, broken lines showing environment or structure are for illustrative purposes only and form no part of the claimed design.

Where included, dotted lines represent the border between claimed and unclaimed subject matter and form no part of the claimed design.
